UNITED STATES PATENT OFFICE

2.369.323

OPERATING MEANS FOR RAILWAY CAR DOORS

William J. Tangerman, Hammond, Ind., assignor, by mesne assignments, to Standard Railway Equipment Manufacturing Company, a corporation of Delaware

Application May 1, 1942, Serial No. 441,308

3 Claims. (Cl. 268—44)

This invention relates to railway car side doors and more particularly to means for moving such doors. The conventional box car has a door opening adjacent the center of each side wall and doors movable in planes parallel with the side walls for closing the door openings.

An object of the invention is to provide rolling means for railway car side doors, which means may be easily brought into operative engagement with the track by movement of a conveniently located handle. A further object is to utilize such handle to engage brackets carried by the track for the purpose of imparting initial movement to the door.

Another object is to provide wedge shaped engaging parts on the door and tracks, respectively, to support the door when the rolling means are disengaged from the track. The wedge provides additional friction to retard movement of the door.

Another object is to provide toggle means for lifting the door and bringing the rolling means into engagement with the track. It is well known that a toggle is well suited for lifting heavy objects, such as railway car doors.

Other objects and advantages of my invention will be apparent from the following detailed description by referring to the accompanying drawings.

In the drawings:

Fig. 1 is a partial side elevation of a railway car including the door and embodying my invention. The rolling means is shown in an inoperative position.

Fig. 2 is an enlarged view of a portion of Fig. 1.

Fig. 3 is a section on line 3-3 of Fig. 2

Fig. 4 is a view similar to Fig. 2 showing the rolling means operatively engaged with the track for moving the door.

The drawings show the usual side door 2 movable horizontally along a track 3 carried by the car adjacent the lower part of the door opening. Housings 5, 6 are rigidly mounted upon the door 2 adjacent the opposite lower corners thereof. Toggles 8 disposed within the housings 5, 6 are comprised of upper (10) and lower (11) links pivotally (13) connected; the upper end of the upper link 10 being pivotally mounted (12) upon the housing and the lower end of the lower link 11 having a roller 14 revolvably mounted thereon. The pin 16 which forms a journal for the roller 14 has its ends slidably engaged in vertically extending slots 17 in the front (19) and rear (20) walls of the housings 5, 6 so that the roller 14 is constrained to move vertically.

A lever 22 is pivotally mounted upon the face of the door 2, preferably midway between the housings 5, 6 and spaced apart blocks 23 are attached to the track 3. The lower end 25 of the lever 22 may be engaged with the blocks 23, as shown in the drawings, to impart initial movement to the door. Connecting members 26, 27 extend from the lever 22 to the center joints 13 of each of the toggles 8. Movement of the upper end 28 of the lever 22 toward the right straightens both toggles 8 and moves the rollers 14 downwardly into operative engagement with the track 3, as shown in Fig. 4, so that the door is then movable upon the rollers 14. The door may then be moved to the full open position by exerting a force upon the lever 22 in the required direction; i. e., toward the right.

A stop 29 is preferably provided on the connecting member 26 within the housing 5 to limit movement of the connecting member 26 and thereby limit the downward movement of the roller 14.

limit the downward movement of the roller 14. The track 3 is comprised of an angle with the inwardly directed leg 32 flared (33) downwardly and inwardly. The housings 5, 6 are provided with pads 35 adapted to engage the flared part 33 of the track 3 and thereby support the door 2 when the lever 22 is released and the rollers 14 move upwardly out of operative engagement with the track. The pads 35 cooperate with the depending outer sides 36 of the housings 5, 6 to straddle and wedge upon the track 3 and thereby frictionally retard movement of the door.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

40 I claim:

1. A door elevating and moving means for a railway car door movable horizontally along a track supported by the car and normally resting thereupon, said means comprising spaced 45 toggles, each having the upper end thereof pivotally attachable to the door and a roller pivotally mounted upon the lower end thereof, said rollers being mountable upon the door for vertically 50 slidable movement, a starting lever mountable intermediate of its ends upon the door for pivotal movement, a connector connecting the knee of each toggle to said lever on opposite sides of the pivot of said lever, and a block carried by the car in the path of pivotal movement 55 of one end of said lever, whereby a pivotal move-

ment of said lever while said lever is engaged with said block forces the rollers against the track and raises the door and simultaneously moves the door horizontally along said track.

2. A door elevating and moving means for a railway car door movable horizontally along a track supported by the car and normally resting thereupon, said means comprising spaced toggles, each having the upper end thereof pivotally attachable to the door and a roller pivotally mounted upon the lower end thereof, said rollers being mountable upon the door for vertically slidable movement, a starting lever pivotally and slidably mountable upon said door, a connector connecting said toggles and operatively associated with said starting lever, a block attachable to the car in the path of pivotal movement of said lever, whereby a force exerted upon said lever straightens both toggles and forces the rollers against the track, raises the door out of engagement with the track, and simultaneously moves the door horizontally along the track.

3. A door elevating and moving means for a railway car door movable horizontally along a track supported by the car and normally resting thereon, said means comprising spaced mechanisms mounted upon the door, each comprising a toggle joint pivotally connected at its upper end to said car and having a roller pivotally connected at its lower end engageable with said track, and means to force said roller against said track, said door being vertically movable relative to said rollers, a starting lever mounted intermediate its ends upon the door for pivotal movement, a connector connecting the knee of each toggle joint with said starting lever on opposite sides of the pivot thereof, and a block carried by the car in the path of pivotal movement of said lever, whereby a pivotal movement of said lever while said lever is engaged with said block forces the rollers against the track and raises the door and simultaneously moves the door horizontally along said track.

WILLIAM J. TANGERMAN
